CLAIM

The ornamental design for a glue gun as shown and described.

DESCRIPTION

FIG. 1 is a front view of a glue gun according to the present application;

FIG. 2 is a rear view of the glue gun according to the present application;

FIG. 3 is a top view of the glue gun according to the present application;

FIG. 4 is a bottom view of the glue gun according to the present application;

FIG. 5 is a left side view of the glue gun according to the present application;

FIG. 6 is a right side view of the glue gun according to the present application; and,

FIG. 7 is a perspective view of the glue gun according to the present application in a partially open position.

1 Claim, 7 Drawing Sheets
